BATTERY FILLER UNIT

Asa H. Mosher, Westfield, N. J.

Application November 4, 1949, Serial No. 5,856

Term of patent 14 years

(Cl. D58—6)

To all whom it may concern:

Be it known that I, Asa H. Mosher, a citizen of the United States, residing at 615 Maye Street, Westfield, in the county of Union and State of New Jersey, have invented a new, original, and ornamental Design for a Battery Filler Unit, of which the following is a specification, reference being had to the accompanying drawing, forming part thereof.

Fig. 1 is a perspective view of a battery filler unit, showing my new design;

Fig. 2 is a top plan view of one of the containers of the unit; and

Fig. 3 is a side view of the container shown in Fig. 2.

I claim:

The ornamental design for a battery filler unit, as shown.

ASA H. MOSHER.
